UNITED STATES PATENT OFFICE

2,329,507

BRUSH REST AND WIPER ACCESSORY

Charles C. Andersen, Chicago, Ill.

Application August 25, 1941; Serial No. 408,198

3 Claims. (Cl. 248—110)

This invention relates to accessories used for attachment to pails, cans, buckets, or other similar articles, and is primarily intended to support a brush or similar article used in connection with the contents of the said pail, can, or bucket.

One object of my invention is to provide a simple device which can be readily attached to and removed from buckets, cans, pails, or other similar receptacles, and one which fits adjustably to varied sizes of such buckets.

Another object of my invention is to provide an accessory of the aforementioned character which may be secured to the rim of a receptacle either at its mid point or at points within a hemispherically sectional area of the opening of the said receptacle.

Another object of my invention is to provide a swivelly or articulately actuated spring clip means which will adapt itself to be attached to the rim of a receptacle at any of a number of different points.

Another object of my invention is to provide an accessory of the aforementioned character which is simple and durable in construction, efficient in use and operation, and of a simple practical structure permitting manufacture in quantity production at but economical expenditures.

With the foregoing objects in mind, other objects may become apparent from a study of the accompanying drawing and the ensuing description wherein like numerals are used to denote like parts and in which:

Fig. 1 is a fragmentary longitudinal cross-sectional view on the line 1—1 of Figure 2.

Fig. 2 is a plan view of a pail or other similar receptacle with my invention secured thereto in different positions, showing the range of positions in which my invention may be secured.

Fig. 3 is a fragmentary perspective view of the novel clip means comprising my invention.

Fig. 4 is a fragmentary graphic representation showing the articulate motion provided in the clip means comprising my invention.

Referring more particularly to Figure 1, and Figure 2, it can be seen that I indicate a standard pail or bucket designated 5 to which my invention is secured. In dotted lines I also show how my invention could be adapted for use with buckets of larger size such as that denoted 6 in dotted lines, or to pails of any size within the maximum range of adjustment.

The elements comprising my invention are namely two, the wire connecting element 13 and the clip member designated 7 which is provided with a rounded semi-circular shaped portion 11

and a bent lip portion 10. The clip member is further provided with a lip or tongue member 8 which abuts against the lip 10 so that the pail or receptacle is confined between the said lip 10 and the tongue 8.

The spring clip element 7 is also provided with a bent lug portion designated 9 which is adapted to be secured to the wire element comprising my invention. The tongue member 8 is adapted to be compressed as indicated by the dotted lines in the view Figure 3 so as to admit the lip 16 of a bucket, can, or other similar receptacle between the confines of the tongue 8 and the lip portion 10.

The bent portion 9 is provided with a drilled hole 12 in order to receive the rod 13 in articulate engagement by virtue of the bent loop portion 14, and at the other extremities, the element 13 being circularly bent to form an eye 15 in order to engage the complementary element 13. There are two elements 13 and two clip members 7 comprising my invention. As can be seen, each element 13 engages the other element 13 in sliding relationship by virtue of the eye portions 15, and each alternate element 13 engages the respective clip member 7 by virtue of the loop portion 14.

In the graphic representation in Figure 4, the limited articulate motion imparted to the member 7 is indicated wherein the corner 19 of the bent portion 9 is shown in abutting relationship with the portion 18 of the element 13 thus showing that the element 7 has articulate motion for approximately 45° on either side of the axis of the element 13. This feature permits the invention to be attached in such position on a pail or receptacle as is indicated in the plan view Figure 2 by the dotted lines. The elements 13, allow by virtue of their sliding engagement, the extensibility of my accessory or invention so that it can be attached as indicated by the dotted lines on a larger pail or receptacle designated 6 as is shown more clearly and elucidated more clearly in Figure 2.

The brush element 17 is caused to rest on the accessory by having its bristles resting on the wire elements 13 and the handle member resting on the rim of the bucket or on the top of the receptacle. In order to attach my invention to a particular receptacle, it is extended to the approximate size of the diameter of the receptacle, and then by grasping the two clip members 7 and pressing them downward, the tongues members 8 will be caused to be sprung inwardly and thus allow the lip 16 of the bucket to pass

between the lip 10 and the tongue 8. When released, the tongue 8 will spring to its normal position and confine the lip 16 of the receptacle confining it in holding engagement with the respective clip member.

After the clips are attached in a central position, the accessory may be shifted to the position embracing less than the diametral distance of the pail 5 as shown in dotted lines of Figure 2, or it may be directly attached in that position to begin with. In removing it, one grasps the two members 7, and by forcing them in an outward direction causing the tongue members to be compressed, thereby providing a space which furnishes clearance to the lip 16 of the receptacle 5 thus permitting lifting of the attachment from disengagement with the receptacle.

As can be seen, the wire member in supporting the bristles on the brush will allow the liquid retained in the brush after use to drain off. When the attachment is used in connection with receptacles whereby it is necessary to constantly dip the brush into the contents of the receptacle, it is preferable to place the attachment in the dotted position indicated at Figure 2 availing the maximum working opening for the brush to be inserted into the receptacle without interference.

I believe I have described rather succinctly the nature and operation of my invention, and inasmuch as it is susceptible of many modifications, alterations, and improvements, I reserve the right to all such modifications, alterations, and improvements, which come within the scope and spirit of my invention, within the embodiment of the accompanying drawing, and within the purview of the foregoing description; my invention to be limited only by the subjoined claims.

Having thus described and revealed my invention what I claim as new and desire to secure by Letters Patent is:

1. In an attachment of the character described adapted to be removably attached to a receptacle, receptacle engaging clip means comprising, a lip portion, a top portion contiguous thereto, a bent over portion contiguous to said top portion provided with means for securing the said clip means articulately, and a V shaped portion contiguous to said bent over portion, the said lip portion overlapping the free end of said V portion.
2. An article of the character described comprising, receptacle engaging clip means having a lip portion, a top portion contiguous thereto, a bent over portion contiguous to said top portion provided with means for securing the said clip means articulately, and a V shaped portion contiguous to said bent over portion, the said lip portion overlapping the free end of said V portion, and extensible rod means articulately secured to the said bent over portion of said clip means.
3. An attachment of the character described comprising a pair of spring clip means adapted to be removably secured to portions of the mouth of a receptacle, and extensible rod means comprising a pair of rod members having a loop portion on each of their ends, the outer loop portions articulately engaging the respective spring clip means, and the inner loop portions slidably engaging the bodies of the said rod members in alternate relationship.

CHARLES C. ANDERSEN.
